UNITED STATES PATENT OFFICE.

WILLIAM H. BROWN, OF TOLEDO, OHIO.

DRAFT-BEAM.

No. 819,835.

Specification of Letters Patent.

Patented May 1, 1906.

Application filed August 14, 1905. Serial No. 274,165.

To all whom it may concern:

Be it known that I, WILLIAM H. BROWN, a citizen of the United States, and a resident of Toledo, in the county of Lucas and State of Ohio, have invented certain new and useful Improvements in Draft-Beams; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to draft-rigging for railway-cars, and has for its object the provision of a cheap, durable, and efficient draft-rigging having integral portions formed on the companion draft-beams thereof, whereby 20 to combine to form a bearing-block for the center pin of a truck and to so lock together as to cause an even distribution of a strain to both beams of the draft-rigging, such arrangement being also made with special provision for accessibility and ready removal of 25 the parts for the purpose of repair.

The construction, operation, and arrangement of the parts of the invention are fully described in the following specification and 30 shown in the accompanying drawings, in which—

Figure 1 is a top plan view of the draft-rigging comprising my invention, together with the associated head-block and upper transom, the latter being partially broken away. Fig. 2 is a bottom plan view of the same with portions of the lower transom broken away. Fig. 3 is a side elevation of the draft-rigging and the portion of a car to which it is secured, 40 with a portion of one draft-beam shown as broken away; and Fig. 4 is a cross-section of the draft-rigging and associated portion of a car, taken on the dotted line xx in Fig. 3.

Referring to the drawings, 1 represent 45 my improved draft-beams, preferably cast from malleable iron or steel, which are of duplicate construction and each made in skeleton form, as shown by dotted lines in Fig. 1, to cheapen and lighten the construction 50 thereof. The companion draft-beams 1 are rigidly bound together in spaced relation by binding-bolts 2, which pass through each of the beams and the spacing members 3, as shown, and are rigidly secured to the two center sills 4 of a car by means of the binding-bolts 5, said bolts passing through a beam

and superimposed sill, as shown. A head-block 6 of suitable construction is bolted in transverse position to the forward end of the beams 1 and has its rear face abutting against 60 the face of the end sill 7, to which it is also bolted.

Formed integral with the inner faces of the companion draft-beams 1 adjacent to their rear ends are the correspondingly-positioned 65 bosses or projections 8, which have their contiguous faces flattened and abutting to form a bearing-block between the beams for the center pin of a truck. The abutting faces of the portions 8 are each formed with a vertical semicircular concavity which register to form the opening or bearing 9 for the reception of the center pin and are formed on opposite sides of said concavities with a vertical tongue and a vertical groove which register, 75 respectively, with the groove and tongue of the other member to form interlocking joints, as shown at 10. The purpose of interlocking the halves of the bearing-block in this manner instead of having their abutting surfaces 80 made plain is to cause a stress on the bearing-block or an unequal stress on the two draft-beams to be equally distributed to both of such beams, as one beam is prevented from a longitudinal movement by the other. While 85 the two sections of the bearing-block are each shown as provided with a tongue and a groove, both tongues may be provided on one section and the grooves on the other, if desired.

The upper and lower surfaces of the portions of the beams 1, from which the block-sections 8 project, are countersunk or grooved a sufficient depth and width to receive the upper and lower transom members 11, the outer surfaces of which are flush with the respective surfaces of the beams, as shown. These transom members are united at their ends to the side sills 4^a, and each is formed with an aperture aligning with the opening 90 through the bearing-block for receiving the center pin.

Mounted between the forward ends of the draft-beams 1 is the usual draw-bar 12, which has the yoke-arms 13 secured to its rear end for receiving the follower-plates 14, which have their ends reciprocally mounted in the pockets 15, provided in transversely-aligning position in the inner sides of the beams 1 and are yieldingly spaced apart by the twin springs 16, as shown.

In addition to the binding-bolts 5 the draft-rigging is further secured against a longitudi-

nal movement with respect to the outer sills by reason of the ribs or raised portions 17, formed on the upper surface of each beam 1, fitting within transverse grooves provided in 5 the lower surface of the center sills.

It will thus be seen that the construction of my draft-rigging materially cheapens and simplifies its manufacture by reason of the center-pin block being cast integral with the 10 draft-beams, that the forming of said block in two sections enables the two beams to be readily separated by the removal of the retaining-bolts for the purpose of repairing or replacing one of the beams, and that the 15 interlocking of the abutting faces of such block-sections strengthens and causes the strain to be more equally distributed to the two draft-beams.

Having thus described my invention, what 20 I claim as new, and desire to secure by Letters Patent, is—

1. In a draft-rigging, two companion draft-beams having integral abutting projections formed on their inner faces to constitute 25 a center-pin block, said projections having their abutting faces interlocked and formed with an opening for a center pin, and means for securing the beams together.

2. In a draft-rigging, two cast-metal beams secured together in spaced relation and having abutting projections formed integral on their inner faces to constitute a center-pin bearing-block, said blocks having their abutting faces formed with vertically-disposed tongue-and-groove connection whereby to 30 prevent an independent longitudinal movement of either beam and also formed with an opening for a center pin.

3. In a draft-rigging, two cast-metal beams secured together in rigidly-spaced relation 40 and provided adjacent to their rear ends with an interposed center-pin block, said block comprising two abutting sections, one of which is cast integral with each beam, and countersunk portions provided in the upper 45 and lower surfaces of each beam in transverse alinement with the center-pin block for the reception of upper and lower transom members.

In witness whereof I have hereunto signed 50 my name to this specification in the presence of two subscribing witnesses.

WILLIAM H. BROWN
